UNITED STATES PATENT OFFICE.

WILLIAM HARRIS, OF PATERSON, NEW JERSEY.

LET-OFF MEANS FOR LOOMS.

Application filed March 13, 1926. Serial No. 94,445.

This invention consists in certain improvements in let-off means for looms of a type which has heretofore been patented to me: see, for example, my Letters Patent #1,548,993.

In the drawings,

Fig. 1 is a side elevation of a loom embodying the invention, certain parts appearing in section; and

Figs. 2 and 3 are sectional views on line 2—2, Fig. 1, showing certain parts in different positions.

1 is the loom frame and 2 a going part, as a rotating shaft of the loom provided with a crank-arm 2^a having a stud 2^b.

Certain means hereinafter described are generally referred to as follows: The rotary means to supply the warp X by A; the flexible attenuated device by B; the paying-out means by C; and the means, tensioning a bight in said device B and controlling means C, by D. Describing these in detail:

Means A in the present example includes the beam 4, having its shaft or trunnion 5 journaled in the loom frame, and a sprocket-wheel 6 fixed thereon.

The device B is in the present case a chain extending in peripheral contact with the under-half of the sprocket-wheel 6 (being engaged with its teeth) as by being slung over suitably journaled idler sprocket-wheels 7; in the present case this chain is endless.

The paying-out means C in the present case comprises the following parts: A combined sprocket-wheel 8 and worm-wheel 9 fixed on a shaft 10 journaled in the frame side, the chain extending over and being engaged with the teeth of the sprocket-wheel; a worm 11 fixed on a shaft 12 which extends parallel with the loom side and forward, having an operating handle or wheel 13 at its forward end, the worm being in mesh with the worm-wheel 9; a ratchet-wheel 14 fixed on shaft 12 and a pawl 15 to engage the teeth of the ratchet-wheel and pivotally connected with one arm of a bell crank lever 16 the other arm of which is connected with a crank pin 2^b by a chain, wire or other flexible connection 17 which preferably extends up over a pulley 18 (the connection at 2^b being a swivel).

The means D includes the following parts: A disk-like sheath 19 revoluble on the

shaft 12, the diameter of which is greater than that of the ratchet-wheel, but having a segmental portion thereof removed to expose some of the teeth of the latter as shown in Fig. 3 at 19^c; a fixed arm 20 projecting between two stop pins 19^a on the sheath; a bell crank lever 21 fulcrumed in the frame to move in a plane parallel with the sheath and connected with the sheath by a spiral spring 22, the upper end of the spring being connected to the lever at a point 22^a above the axis (12) of the sheath and its lower end to the sheath at a point 22^b below said axis; a sprocket-wheel 23 engaged in a bight B' of the chain depending between sprocket-wheel 8 and the near idler sprocket 7; and a weight carrier 24 hung from the central spindle 23^a of the sprocket-wheel and adjustable lengthwise of and on a lever 25 which is fulcrumed in the frame and has an arm 25^a engaged in a slot 21^a of lever 21.

When the loom is running, the parts being in the position of Fig. 3, the device B is pulled by means A in the direction of the arrow in Fig. 1 and at the same time it is being paid out by means C, the pawl 15 of which, kept oscillating constantly from stud 2^b, is then moving the ratchet wheel 14 step by step and so through 11—9 rotating the sprocket-wheel 8. This paying-out, by proper designing and timing of the parts, is made faster than the take-up of said device by means A, so that the bight will increase and there will be a corresponding descent of lever 25 and shifting of lever 21 from the position in Fig. 3 to that in Fig. 2 (or clockwise), resulting in the sheath ultimately undergoing a sudden rotary (anti-clockwise) shifting sufficiently to clear and hold the pawl 15 disengaged from the ratchet-wheel, whereupon the paying-out ceases. Taking-up of the bight then proceeds, lever 25 consequently rising and shifting lever 21 in the anti-clockwise direction, resulting in the sheath undergoing a sudden rotary (clockwise) shifting sufficiently to allow the pawl again to engage the ratchet-teeth, wherefore the taking-up of the bight ceases.

By utilizing a worm and worm-wheel the means C includes intermeshing rotary parts with one of which (9) the device B is in tractive engagement and the other of which (11) has its meshing portion pitched transversely of its axis of rotation and normally positively locks the first-named part against

independent rotation; thus I simplify the gearing and eliminate any need for an independent brake, and at the same time I provide a simple means whereby when the loom is stopped the warp can be slackened, which is accomplished by turning the gear member 11 by means of the hand-wheel 13 in the direction to pay-out the device B.

The mentioned sudden movements of the sheath are due to its spring-toggle connection with lever 21. When this lever shifts in either direction the spring holds the sheath in its initial position until point 22^a passes a straight line connecting 22^b and 12, whereupon the spring becomes active to shift the sheath—in the direction relatively opposite to the ensuing movement of the lever. In other words, 19 is an actuated member rotatable back and forth between given limits, 21 an actuating member movable back and forth and so that a part (22^a) thereof travels past the axis of member 21 at one side of said axis, and the spring is elastic means connecting said part with the actuated member at the opposite side of said axis.

Having thus fully described my invention what I claim and desire to secure by Letters Patent is:—

1. Mechanism to control the letting-off of a warp in a loom including a rotary element urged to rotate in one direction under the pull of the warp, rotary paying-out means, a flexible attenuated device having a bight between and being in tractive engagement with said element and a rotary part of said means and extending from the former oppositely to its said direction of rotation, and

means to tension the bight, the first-named means including with said part another rotary part meshing therewith and having its meshing portion pitched transversely of its axis of rotation and normally positively locking the first-named part against independent rotation.

2. A controlling mechanism for the purpose described including an actuated member rotatable back and forth between given limits, an actuating member movable back and forth so that a part thereof travels past the axis of the actuated member at one side of said axis, and means elastically connecting said part with said actuated member at the opposite side of said axis.

3. In combination, rotary means to supply the warp including a rotary element on which the warp is wound, a flexible attenuated device in tractive engagement with and having a portion thereof extending from a rotary part of said means relatively reversely to the direction in which the warp extends from said element and formed with a bight, rotary means to pay out said device at a rate to increase said bight including a rotary member and means to advance the same step by step shiftable into and out of engagement with said member, means to tension the bight movable back and forth as the bight varies in extent, and toggle means controlled by the last-named means and controlling the shifting of the advancing means.

In testimony whereof I affix my signature.

WILLIAM HARRIS.
